FEEDING MECHANISM FOR WEB MATERIAL.

1,286,308.

Specification of Letters Patent.

Patented Dec. 3, 1918.

Application filed December 30, 1915. Serial No. 69,461.

To all whom it may concern:

Be it known that I, EDGAR M. HAWKINS, a citizen of the United States, and resident of Rochester, in the county of Monroe and 5 State of New York, have invented certain new and useful Improvements in Feeding Mechanism for Web Material, of which the following is a specification.

This invention relates to a feeding mechanism for feeding a web of material to a machine adapted for performing certain operations thereupon, and it may be made a part of such a machine or be separately mounted for coöperation therewith, as de- 10 sired. In the present case, it is shown as part of a machine forming the subject-matter of an application of C. R. Seymour and O. M. Hoch, Serial No. 69,097 filed December 28, 1915, which is especially designed for 15 receiving a web of single-faced or double-faced corrugated board, and to cut the same into blanks or portions of predetermined length, and then to trim the edge portions of the blanks so formed, and if desirable, pro- 20 vide the blanks with bending creases. This machine was designed especially for re- ceiving single-faced or double-faced corrugated board manufactured upon a machine 25 constructed for the purpose and is intended 30 to be located at the rear of the latter machine to receive the board directly therefrom, the two machines when so used constituting in effect a single machine.

The feeding mechanism of my present 35 invention is so positioned as to receive the web of corrugated board from the forward part of the machine where it is produced, and feed the same to the rear part of the machine where it is operated upon in the 40 manner referred to. This feeding mechanism comprises coöperating feed rolls which, when properly adjusted, will ordinarily impart the desired continuous and uniform feeding of the web. If, however, 45 there should occur a break in the web, or a section of the same should be of less than usual thickness, then an interruption in the normal feeding of the web would occur, and this, when the web is being fed directly 50 from the front part of the machine to the rear part, is liable to result in a clogging of the machine. Therefore, it has been the object of my present invention to provide a 55 means, for use in coöperation with the regular feed rolls, that will be under the manual

control of the operator at all times for quickly restoring the feed of the web when interrupted, without stopping or otherwise interfering with the regular operation of the machine. This object I accomplish, in 60 one form of my invention, by combining with a pair of feed rolls, a pair of supplemental feed rolls between which the web passes and which are normally spaced to conform with the space between said feed 65 rolls, and means under the control of the operator for quickly bringing such supplemental rolls into closer relation to compensate for any reduction in thickness of the web and so assure continued feeding of the 70 web.

The invention is illustrated in the accompanying drawings, in which:—

Figure 1 is a longitudinal vertical section through the central portion of a machine 75 provided with my improved feeding mechanism;

Fig. 2 is a broken plan view, partly in section, of that part of the structure shown in Fig. 1 which is provided with the feeding 80 mechanism; and

Fig. 3 is an enlarged vertical section of the rear part of the feeding mechanism.

These views substantially correspond with views in the aforesaid Seymour and 85 Hoch application, in which the feeding mechanism of the present application is fully disclosed, but not claimed.

The various operating parts of the machine are mounted upon a suitable frame- 90 work, denoted generally by the reference character A. At the forward end of this frame-work are a plurality of pairs of feed rolls. In the present instance, there are four pairs of such rolls, the rolls of the first 95 pair being shown at 1, those of the second pair at 2, those of the third pair at 3, and those of the fourth pair being shown at 4. As above stated, the faced corrugated board discharged from the forward part of the 100 machine not herein shown is gripped by these rolls and fed to the present machine. The four pairs of rolls just mentioned may, therefore, be more properly termed "pull" rolls, as they pull the material from the 105 rear end of the machine for manufacturing the faced corrugated board and feed the same to the present machine.

The top rolls of the first three pairs are made adjustable toward and away from the 110

- 2
- lower rolls of such pairs by mounting the journals of the same in bearing boxes 5 (Fig. 3) capable of vertical sliding movements in the side frames of this part of the machine.
- 5 The lower roll of each pair is mounted in stationary bearing boxes 6 over which the bearing boxes 5 are yieldingly supported by means of coil springs 7. It will be understood that there is an upper sliding box 5 at 70 each side of the machine for each upper roll of the first three pairs and a lower box 6 at each side of the machine for each of the lower rolls of the first three pairs, and that a spring 7 serves to support each upper box 5 75 upon the lower box 6. All of the upper boxes 5 are provided with bosses 8, each of which is internally threaded to receive a rotatable screw shaft 9. Each of the screw shafts 9 is rotatably mounted in and extends upwardly 80 10 through a bearing bracket 10 mounted upon the corresponding side frame, and above such bracket each screw shaft is provided with a beveled gear 11. The beveled gears 11 of each pair are rotated from a trans- 85 15 verse shaft 12 carrying two beveled pinions 13 to mesh with the two beveled gears 11 of each pair. There are, therefore, three trans- 90 20 verse shafts 12, each of which carries two beveled pinions 13 for rotating the beveled 95 25 gear 11 at each end of one of the rolls. Each of the transverse shafts 12 is provided with a hand wheel 14, by means of which such shaft may be rotated to adjust the position of the corresponding upper roll toward and 100 30 away from the underlying bottom roll. It will be obvious that the turning of any one of the shafts 12 will simultaneously rotate the screw shafts 9 at the opposite ends of the corresponding upper feed roll to raise or 105 35 lower the two boxes 5 in which such roll is mounted. The springs 7 serve to hold the upper rolls the proper distance away from the lower rolls and when the upper rolls are adjusted toward the lower rolls, they are 110 40 moved against the tension of the springs 7. The adjusting mechanism just described is utilized to space the upper roll of each pair the proper distance from the corresponding lower roll to feed the faced corrugated board 115 45 without crushing the same.
- 50 It will be noted that the top roll 4 of the fourth pair of rolls is not adjustable by the same type of mechanism as that just described. The top roll 4 of this pair is 55 mounted in upper sliding boxes 5 the same as the other top rolls, and the lower roll 4 is mounted in boxes 6 similar to the boxes 6 employed for the other lower rolls, and the upper boxes 5 are supported on the lower 60 boxes 6 by means of springs 7, just as in the case of the first three pairs of rolls. Each of the top boxes 5, however, of the top roll 4, receives the threaded extremity of an arm 65 15, which extremity is locked to the box 5 by means of a lock nut 16. On each of the side frames is mounted a bracket 17 to which the extremity of a link 18 is pivoted. Each of the arms 15 is pivoted to the mid-portion of the corresponding link 18, as shown at 19. The two links 18 are swung upon the 70 75 80 85 90 95 100 105 110 115 120 125 130 side frames 17 to raise and lower the upper roll 4 by means of a lever 20 disposed at one side of the machine and rigidly secured to a rock shaft 21. The rock shaft 21 at each side of the machine carries a rock arm 22 connected by means of a short link 23 to the extremity of the corresponding link 18. The lever 20 has connected thereto, a chain or cord 24 (Fig. 1) which may extend to an operator's station at the front portion of the machine. 80 In the normal position of the parts, the toggles constituted by the arms 22 and links 23 are straight, in which position the arms 22 abut against set screws 25. In this position of the parts, the top roll 4 is in its 85 raised position and is spaced from the corresponding lower roll 4. The set screw 25, therefore, determines the spacing between these rolls. In the normal position of the rolls 4 of the fourth pair, they pinch the 90 faced corrugated board slightly and assist the first three pairs of rolls in feeding the same forward. As above stated, the extent of this pinching action may be regulated in the case of the first three pairs of rolls by 95 turning the hand wheels 14. When these wheels are turned in one direction, the upper boxes 5 of the top rolls of the first three pairs will be lifted by the springs 7, and when turned in the opposite direction, the screw 100 shafts 9 will force the top boxes 5 downwardly against the tension of the springs 7. The space between the rolls of the fourth pair is adjusted to conform with the space between the rolls of the other pairs by turning the set screw 25. If, for any reason, there may be a break in the paper passing through the machine and it is desired to start a new portion of the web through the machine, the lever 20 is actuated to depress 105 the top roll 4 and bring it into contact with the corresponding lower roll 4. It may also be desirable to do this in the event that the faced corrugated board passing between the feed or pull rolls is of less than normal 110 thickness, as may be the case if the material for forming the corrugated filler gives out, in which event, the web would not be properly fed forward by the pull rolls. By actuating the lever 20, the top roll 4 may be 115 quickly brought into closer relation with the corresponding bottom roll to compensate for the reduction in thickness of the web, and, therefore, the web will be fed forward and will not clog the machine. When the 120 pull upon the lever 20 is released, the upper roll 4 will return to its normal position, due to the provision of the springs 7 which support the upper boxes of the top roll 4. 125 These feed or pull rolls may be driven 130

by any suitable means. As here shown, they are driven from a shaft 154 which loosely carries a beveled gear 155 meshing with a beveled pinion 156 upon a drive shaft 151 arranged at one side of the machine. A clutch 157 serves to connect or disconnect the gear 155 with the shaft 154. This clutch may be operated by means of a pivoted lever 158 which, in turn, may be actuated by means of a rod 159 running to the side of the machine and actuatable by a handle 160 (Fig. 2). The shaft 154 carries at its end remote from the gear 155, a pinion 161 which meshes with two gears 162. Each of these gears is mounted upon a shaft 163 which extends back to the drive side of the machine. At this side of the machine each of the shafts 163 carries a pinion 164, which serves to drive a gear 165 mounted upon one of the shafts of each pair of pull rolls. It will be understood that the two pull rolls of each pair are geared together by two gears 165 and that as one of such gears of each pair is driven by an adjacent pinion 164, all of the feed rolls are positively driven.

The machine here shown as provided with my improved feeding mechanism, is also provided with a shear mechanism, indicated generally by the reference character B, for cutting the web transversely into predetermined lengths; and with a creasing and slitting mechanism, indicated generally by the reference character C, for creasing and trimming the cut blanks. The particular character of the machine in connection with which my improved feeding mechanism is employed, however, is immaterial, as will be understood.

The preferred form of feeding means has been specifically described, but it will be obvious that the parts of the same may be constructed in other ways than that described, without departing from the spirit or scope of the invention as defined in the accompanying claims.

What I claim is: —

1. In a machine for operating upon a web

of material, the combination of a pair of feed rolls adapted to feed the web to the machine, a pair of rolls disposed at the rear of said feed rolls, means to adjust the distance between the rolls of each pair, and means under the control of the operator for quickly bringing the rolls of the latter pair into closer relation with each other.

2. In a machine for operating upon a web of material, the combination of at least two pairs of rolls adapted to feed the web to the machine, said rolls being normally spaced a predetermined distance apart, and means under the control of the operator for quickly bringing the rolls of one of the pairs into closer relation with each other during the operation of the machine, for the purpose described.

3. In a machine for operating upon a web of material, the combination of a plurality of pairs of rolls adapted to feed the web to the machine, a pair of supplemental rolls between which the web passes, the rolls of each pair being set a predetermined distance apart, and means under the control of the operator for quickly bringing the rolls of said supplemental pair into closer relation with each other during the operation of the machine.

4. In a machine for operating upon a web of the material, the combination of a pair of rolls adapted to feed the web to the machine, means to adjust said rolls a predetermined distance apart, a pair of supplemental rolls between which the web passes, and means under the control of the operator for quickly bringing the supplemental rolls into closer relation with each other during the operation of the machine, for the purpose described.

Signed at Rochester, in the county of Monroe, and State of New York, this 28th day of December A. D., 1915.

EDGAR M. HAWKINS.
